UNITED STATES PATENT OFFICE.

ROBERT KELLER, OF DETROIT, MICHIGAN.

PASTE-TUBE.

1,122,006.

Specification of Letters Patent. Patented Dec. 22, 1914.

Application filed December 23, 1912. Serial No. 738,116.

To all whom it may concern:

Be it known that I, ROBERT KELLER, a citizen of the United States of America, residing at Detroit, in the county of Wayne 5 and State of Michigan, have invented certain new and useful Improvements in Paste-Tubes, of which the following is a specification, reference being had therein to the accompanying drawings.

10 This invention relates to improvements in collapsible containers for paste and other semi-liquid substances, and more particularly to provide said containers with means for spreading the material over the surface 15 face to which it is to be applied as it issues from the container.

The object of this invention is to provide the container with a flexible strip adjacent to its discharge opening and construct the 20 container with simple and efficient means for securely holding the spreader in place.

To this end the invention consists in the matters hereinafter set forth and pointed out in the claims reference being had to the 25 accompanying drawing in which—

Figure 1 is a side elevation of a collapsible container embodying the invention; Fig. 2 is a similar view taken at right angles to that of Fig. 1; Fig. 3 is a plan view with 30 the closure pin removed; and Fig. 4 is a transverse vertical section through the upper portion of the container.

As shown in the drawing, the body 1 of the container is formed of a collapsible sheet 35 metal tube in an old and well known manner, the same having a bottom closure 2 formed by flattening and folding over the end of the tube, and an integral upper head or end 3. The head 3 is formed with a 40 nipple 4 having a discharge opening 5 adapted to be closed by a pin 6, all in an old and well known manner.

This invention consists in forming the head 3 with a flange or lip 7 extending outwardly adjacent to the side of the nipple with a space between the flange and nipple forming a groove to receive a flexible strip 8 of rubber or other suitable material of a length to project outward some distance 50 beyond the end of the nipple. The nipple 4 is preferably formed with a flat side opposing the flange 7 against which side the flexible spreader 8 is firmly secured within the groove between the nipple and flange, 55 by bending or forming the flange inwardly toward the nipple and thus firmly clasping

the flexible strip between it and the flattened side of the nipple. The spreader 8 is thus positioned and firmly held transversely of the tube adjacent to one side of the discharge opening 5 and thus when material is forced from the container by compressing its collapsible sides, said material may be spread over the surface to which it is desired to apply it by means of the outwardly 60 extending flexible strip which will bend laterally when pressed against the surface and spread the material evenly and smoothly over it. A very inexpensive and efficient spreading attachment for devices of this 65 character is thus secured and the spreader is firmly held in place by the inwardly bent flange, the strip by reason of its resiliency being compressed by the bending of the upper end of the flange into engagement 70 with it. The strip being formed of flexible material and being a thin flat piece will not become stiff and clogged with material by use and present a flat, smooth surface 75 for spreading the material from the container.

Obviously, changes may be made in the construction and form of the means for holding the spreader in place on the container and other changes in the construction 80 and arrangement of parts may obviously be made without departing from the spirit of my invention and I therefore do not wish to limit myself to the particular construction 85 shown.

Having thus fully described my invention what I claim is:—

1. The combination of a collapsible tubular container having a concentric cylindrical nipple at one end thereof provided with a discharge opening and a flat rigid side adjacent to the opening of said nipple, a malleable flange forming a part of said nipple adjacent to the flat side thereof, and a flexible strip secured at one end between said flange and the flat side of said nipple by bending the flange into engagement with the flat side of the strip.

2. The combination of a collapsible tubular container having a head formed with an integral rigid concentric cylindrical nipple provided with an eccentrically disposed discharge opening, said nipple having a groove formed therein providing a segment-shaped malleable flange spaced from said nipple and cooperating therewith in providing confronting flat surfaces, a strip of

- flexible material secured at one end between the flat surfaces of said nipple and said flange by bending the flange to clamp the strip between it and the nipple with the outer end of said strip projecting beyond the end of the nipple at one side of the discharge opening.
3. A container having a closed end, a rigid nipple formed integral therewith and provided with an eccentric discharge opening, said nipple having a groove formed therein adjacent to said opening and pro-

viding a malleable flange, and a strip of flexible material arranged in the groove of said nipple and retained therein by bending said flange toward the body of said nipple. 15

In testimony whereof I affix my signature in presence of two witnesses.

ROBERT KELLER.
